UNITED STATES PATENT OFFICE.

ROBERT A. SUMMERS, OF VAN NUYS, CALIFORNIA.

ADJUSTABLE STILT.

1,418,685.

Specification of Letters Patent. Patented June 6, 1922.

Application filed October 15, 1919. Serial No. 330,868.

To all whom it may concern:

Be it known that I, ROBERT A. SUMMERS, a citizen of the United States, residing at Van Nuys, in the county of Los Angeles and 5 State of California, have invented a new and useful Adjustable Stilt, of which the following is a specification.

This invention relates to stilts adapted to enable the person using the same to master 10 the art of walking with stilts of considerable height by the use of adjustable foot rests, so that the learner or other user of the stilts may begin walking at a low height and may ascend to a greater height.

15 This invention relates more particularly to the specific construction of the foot rest operating on the standard or stilt bar.

An object is to provide a simple, strong 20 construction which can be easily manufactured and can be easily operated by the learner or other person.

Other objects, advantages and features of 25 invention may appear from the accompanying drawing, the subjoined detail description and the appended claims.

The accompanying drawing illustrates the invention.

Figure 1 is a fragmental perspective view 30 of a stilt constructed in accordance with this invention.

Fig. 2 is a view of a pair of stilts in use.

1 is the standard having notches 6 on one edge and a stop 10 near the bottom. 2 is the slide having a pawl 4 pivoted at 5 there- 35 to, and also having a runner 9 fixed to the slide and running along the notched face of the standard. The pawl 4 is of sufficient width at the top to permit a foot rest recess 3 to be formed in the top thereof be- 40 tween the side lugs 11, 12. The pawl may be made of wood with the notch 3 cut into the top thereof as indicated.

A strap 8 is secured to the top of the pawl on the side thereof next to the runner 45 9 and extends over the lug 11 and the lug 12 and is provided with one or more holes 13 adapted to fit upon a stud 14 inserted into the outer side of the pawl so that the user can easily adjust the strap to fit his 50 foot as indicated in Fig. 2. The notches 6 have a sloping upper wall 15 and a bottom wall 16 which is at right angles to the face 17 of the standard into which the notches are cut. The tip 7 of the pawl is prac-

tically conformed to the notch into which it fits.

In practice the user by placing his foot into the notch 3 between the lugs 11 and 12 and drawing the strap 8 tightly down upon the foot and hooking it upon the stud 14 60 secures the foot rest to his foot. This is done with each of the foot rests and the user then walks as indicated in Fig. 2 and can climb up to a greater height without dismounting by simply raising his foot, moving it toward the face 17 of the standard while he lifts his foot and moving it outward while bringing the foot to rest. The inward or lateral movement of the foot acting on the lug 11 throws the point 7 out of 65 the notch and the reverse movement brings the foot against the lug 12 and moves the point 7 into the notch.

This construction can easily be made of strong wood, and will serve all purposes, being light and not likely to rust.

The runner 9 projects below the slide and also projects above the level of the lug 11 and consequently rides over the notches without any likelihood of being 80 forced thereinto by the movement of the foot required to displace the tip 7 from the notches 6. The strap is fastened to that side of the pawl which is nearest the notched face of the standard so that in practice the 85 user can readily attach the loose end of the strap to the stud which is on the side farthest from said notched face.

The stop 10 between the notches and the bottom of the standard is adapted to intercept the slide to allow the stilt to be carried without danger of losing the slide.

I claim:

1. A stilt comprising a standard having a notched face, a slide movable upon said standard, a pawl pivoted to the slide and having a tip at its lower end adapted to engage the notches; said pawl being provided at its top with a recess between two lugs to accommodate the foot of the user, 100 and also being provided with a stud on the side farthest away from the notched face of the standard; a strap fastened to the pawl on the side nearest to the standard and extending over the lugs and provided with 105 one or more holes to engage the stud; and a runner fixed to said slide which projects below the slide and also projects above the

level of the lug nearest to the standard so as to intercept said lug from entering said notches when the tip of the pawl is moved out of engagement with the notches 5 when raising the pawl on the standard.

2. In a stilt comprising a standard having a notched face and a slide on said standard, a pawl pivoted to the slide and provided with a tip below the slide to engage the 10 notches on the notched face, and provided above the slide with a recess between two lugs and a strap extending over said lugs

and recess; a runner fixed to said slide between said pawl and said notched face, and which extends above and below said slide 15 for the purpose as set forth; and the tip of said pawl being disengaged by lateral pressure toward the standard.

In testimony whereof, I have hereunto set my hand at Los Angeles, California, 20 this 8th day of October, 1919.

ROBERT A. SUMMERS
